UNITED STATES PATENT OFFICE

CLAUDE BETHEL, OF WILKINSBURG, PENNSYLVANIA, ASSIGNOR TO WESTINGHOUSE ELECTRIC & MANUFACTURING COMPANY, A CORPORATION OF PENNSYLVANIA

INTEGRAL MINING LOCOMOTIVE

Application filed March 17, 1930. Serial No. 436,391.

My invention relates, in general, to electric locomotives and, more particularly, to small locomotives of a type suitable for mining service.

5 An object of my invention, generally stated, is to provide a locomotive which shall be simple and efficient in operation and which may be readily and economically manufactured.

10 A more specific object of my invention is to provide for resiliently mounting, on the driving axles of a locomotive, an integral locomotive frame of which the motor housings form a part.

15 Another object of my invention is to provide for securing the axle bearings of locomotives in their proper operating relation to the locomotive frame and in such manner that the axles may move relative to the locomotive frame when the locomotive passes over irregularities in a track.

20 Still another object of my invention is to provide for removing the armatures of the driving motors from the motor housings without removing the wheels and axles from the locomotive.

25 Heretofore, in the design of mining locomotives, it has been customary to utilize a locomotive-frame structure comprising a frame which is resiliently mounted on the driving axles and serves to support independently mounted driving motors.

It has also been customary to mount the locomotive frame on the wheel axles by means 30 of journal boxes that are disposed within pedestal jaws attached to the sides of the locomotive frame. The journal boxes are guided by the pedestal jaws in such manner that they are free to move vertically therein. The 35 weight of the locomotive is carried by springs which are interposed between the tops of the journal boxes and the upper ends of the pedestal jaws.

According to this invention, the frames of 40 the driving motors and the locomotive frame are cast integrally to form a unitary structure. By reason of this construction, the motor housings are utilized for the double purpose of enclosing the motors and giving mechanical strength to the locomotive frame,

thereby providing a locomotive frame having a small number of parts and of comparatively light and rigid construction.

In the present invention, the journal bearings are retained in their proper operating 55 position by means of a torque arm which cooperates with a disc spring to prevent the bearing housing from rotating and to limit the longitudinal and lateral movement of the driving axle. This method of construction avoids the use of the pedestal jaws formerly 60 provided to guide the journal boxes and thereby makes unnecessary the expensive planing and milling operations required in 65 making the pedestal guides.

For a fuller understanding of the nature and objects of the invention, reference may be had to the following detailed description, taken in conjunction with the accompanying 70 drawings, in which:

Figure 1 is a top plan view of a portion of an electric locomotive embodying the principles of my invention;

Fig. 2 is a view, partly in elevation and partly in section, showing details of the construction of a journal bearing and supporting spring;

Fig. 3 is a plan view of the locomotive frame and

Fig. 4 is a view, in side elevation, of the 80 locomotive frame shown in Fig. 3.

In order to simplify the drawings, I have shown the details of construction of only a part of a locomotive that embodies my invention. The locomotive, as illustrated, comprises a unitary motor housing and frame 10 that is composed of a pair of motor-housing portions 11 formed integrally with the side-frame portions 12. A combination bumper and draw-bar 13 may be provided at each 90 end of the locomotive frame. The bumpers may be cast integrally with the frame or cast separately and attached to the frame.

In order to provide space for a motorman's 95 compartment and for mounting the necessary control equipment for operating the locomotive, a platform 14 is provided which extends laterally from the side-frame members 12.

The locomotive frame is supported on a 100

pair of axles 15 each of which is provided with two wheels 16 and two journal bearings 17 that are disposed between the wheels 16. Each of the journal bearings 17 comprises a housing 18 having a cylindrical opening for receiving a bearing sleeve 19.

In structures of this type, any standard lubricating system may be utilized. In the present case, the journal bearings 17 are provided with a lubricating system comprising an oil reservoir 20 and a wick chamber 21 such as are embodied in the oil-sealed lubrication device disclosed in Patent No. 1,535,560, issued to Claude Bethel and Edwin Tidlund and assigned to Westinghouse Electric and Manufacturing Company.

In order to resiliently support the locomotive frame 10, springs 23 are interposed between the top portion of each journal bearing 17 and the frame 10. The springs 23 are of the disc type disclosed by Winston A. Brecht in copending application, Serial No. 293,542, filed July 18, 1928, now Patent No. 1,826,597, issued October 6, 1931, and assigned to Westinghouse Electric and Manufacturing Company. The springs are composed of annular discs of radially tapered cross section which are stacked with suitable spacing members in axial alignment to form a spring system of any desired height and resilience.

Since the spring mechanisms, as thus constructed, possess lateral stability or resistance to forces at an angle to the axis of the spring, they may be utilized to limit the journal boxes 17 to motion in substantially a transverse plane of the locomotive frame 10 and in proper longitudinal relation thereto, thereby restraining the lateral and longitudinal movement of the driving axles 15.

In order to prevent the bearing housing 18 from rotating about the axle 15, it is provided with a torque arm 24 which is attached to the frame 10 by means of lugs 25 and 26. In order to permit the axle 15 to have free oscillatory movement, so that the wheels 16 can pass over irregularities in a track, the end of the torque arm 24 is retained between the lugs 25 and 26 by means of a ball-and-socket joint 27.

It will be seen that the torque arm 24 and the disc spring 23 cooperate to restrain the driving axle 15 from movement in a horizontal direction, relative to the frame 10, but permit movement of the axle in a substantially vertical direction.

In order to transmit power from the armature shafts, which are mounted in the housings 11, to the resiliently mounted driving axles 15, spherically seated flexible gear wheels 28, similar to the one shown in my Patent No. 1,602,298, may be utilized. Such gear wheels, as disclosed in the patent, are adapted for the transmission of power be-

tween shafts which are subjected to conditions of slight misalignment.

In order that the armatures of the motors may be removed from the motor housings without removing the wheels and axles from the locomotive, the frame is so shaped that, with the sandboxes 30 removed, the wheels, together with the bearings and the gear case, may be rolled forward far enough for the wheels to clear the housings and permit the armatures 31 to be removed. In case it becomes necessary to remove a motor armature, the locomotive frame may be raised, by means of jacks or other tools, to remove its weight from the journal bearings. The torque arms 24 may then be released by removing the lugs 26 from the frame, and the wheels rolled forward, as described above.

Although I have described a specific embodiment of my invention, it will be obvious to those skilled in the art that various modifications may be made in the details of construction and in the arrangement of the cooperating parts without departing from the spirit and scope of the invention as defined in the appended claims.

I claim as my invention:

1. In a railway locomotive, in combination, an integral motor housing and locomotive frame member, a wheel axle for carrying said member, a motor provided with an armature shaft mounted in the housing, means for transmitting power from the armature shaft to the wheel axle, and means for normally restricting the wheel axle to substantially vertical movements relative to the frame, said means being disposed to permit the wheel axle to be moved longitudinally of the frame to permit the motor armature to be removed from the motor housing. 100

2. In a railway locomotive, in combination, an integral motor housing and frame member, a plurality of wheel axles for carrying said member, a plurality of motors having independent armature shafts mounted in the housing, means for transmitting power from the armature shafts to the wheel axles, and means for normally restricting the wheel axles to substantially vertical movements relative to the frame, said means being disposed to permit the wheel axles to be moved longitudinally of the frame to permit the motor armatures to be removed from the motor housing. 110

3. In a railway vehicle, in combination, an integral motor housing and vehicle frame member, a wheel axle for carrying said member, a motor provided with an armature shaft mounted in the housing, a plurality of gears for transmitting power from the armature shaft to the wheel axle, resilient means for supporting the vehicle frame on the axle, and a torque arm disposed to cooperate with said resilient means to normally restrict the axle to substantially vertical movements with 120

respect to the frame, said torque arm being disposed to permit the wheel axle to be moved longitudinally of the frame when the weight of the vehicle is removed from the resilient means to permit the motor armature to be removed from the motor housing.

4. In a railway vehicle, in combination, an integral motor housing and vehicle frame member, a plurality of wheel axles for carrying the frame, a plurality of motors having independent armature shafts mounted in the housing, a plurality of gears for transmitting power from the armature shafts to the wheel axles, spring means comprising a plurality of annular discs of radially tapered cross section for supporting the vehicle frame on the axles, and torque arms disposed to cooperate with said spring means to normally restrict the axles to substantially vertical movements with respect to the frame, said torque arms being disposed to permit the wheel axles to be moved longitudinally of the frame when the weight of the vehicle is removed from the spring means to permit the motor armatures to be removed from the motor housings.

In testimony whereof, I have hereunto subscribed my name this 5th day of March 1930.

CLAUDE BETHEL.
